ROOM COOLER

Joseph Federico, Buffalo, N. Y., assignor to Carrier Corporation, Syracuse, N. Y., a corporation of Delaware

Application January 27, 1954, Serial No. 28,699

Term of patent 7 years

(Cl. D62—4)

Fig. 1

The essential features of the design are shown in full lines.

I claim:

The ornamental design for a room cooler, as shown and described.
